United States Patent Office.

HENRY E. BODWELL, JR., OF SOUTH NORWALK, CONNECTICUT.

Letters Patent No. 95,874, dated October 19, 1869.

IMPROVEMENT IN TUCKING-ATTACHMENT FOR SEWING-MACHINES.

The Schedule referred to in these Letters Patent and making part of the same.

To all whom it may concern:

Be it known that I, HENRY E. BODWELL, Jr., of the town of South Norwalk, county of Fairfield, and State of Connecticut, have invented a new and useful Improvement in Tuckers for Use on Sewing-Machines; and I do hereby declare that the following is a full and correct description thereof, reference being had to the accompanying drawing and to the letters of reference marked thereon.

The nature of my invention consists in the arrangement of parts, as hereinafter described, for regulating and folding the cloth to form any required width of tuck.

To enable others skilled in the art to make and use my invention, I will proceed to describe the same.

In the drawing—

Figure 1 is a view of the tucker as placed on the table of a sewing-machine.

The flat plate A is formed, as shown in the drawing, with a slot, B, and set-screw, C, for attaching firmly to a table, with a loose hinged folding-plate, D, at the end to regulate the width of the tuck.

This plate D is adjustable, by means of the pin F, which passes through the hinge-joint, so that several plates of different widths can be substituted to fold any required width of tuck.

The forming-plate E is made, as shown in the drawing, with an arm sliding in the flat socket G to the bottom of the vertical slotted plate H.

This vertical slotted plate H rises up at a right

angle from the slide-socket G, and is attached to the arm K, by means of the set-screw M, so as to be adjustable, to regulate the width of the tuck.

The guide L is attached on to the flat socket G by the set-screw and slot I I, so that it can be adjusted to the distance for the finished tuck to slide in.

The arm E of the forming-plate E slides in the flat socket G, and is removable by being withdrawn for the convenience of placing on the cloth for operation.

The arm K, as shown, is not the necessary arm for supporting the plate H of the tucker, as there are several ways of attaching it, so as to be in a proper position near the needle for operating.

The edge of the plait previously formed is entered in the guide L. The end of the cloth is then passed between the plates E and A D; and the plate D is then turned over the edge of E, taking with it the cloth, and laying it in the form of a fold, the end of the cloth yet being to the left.

What I claim as my invention, and desire to secure by Letters Patent, is—

The adjustable sliding-plate A, the hinged folding-plate D, the forming-plate E, and regulating-guide L, all constructed and arranged as and for the purpose specified.

HENRY E. BODWELL, JR.
